VARIABLE SPRAY NOZZLE

Ruisaburo Fukuyama, Higashi-Sumiyoshi-Ku,
Osaka, Japan

Application April 30, 1951, Serial No. 223,675

Claims priority, application Japan
January 5, 1951

2 Claims. (Cl. 299—136)

1

This invention relates to an improvement of a variable spray nozzle with the following mechanism: The casing is connected to the end of the pipe. The base of the narrow portion of the said casing is equipped with the divided holes geared with the male screw at the lower outside of the said casing. Thus the branch stream straight shooting casing is made to move back and forth by gyration. The inside surface of the upper end of the said branch straight shooting casing and the outside surface of the narrow portion of casing are made to form the straight shooting jet. The spray cover is screwed with the female screw which is provided on the inside of the narrow portion of the casing. The water supplying holes are provided at the middle side of spray cover. The guide flange is fitted at the upper end of the spray cover. The shallow groove is provided at the top of the guide flange. By fitting the end of driver in this shallow groove and turning it, the space between the lower surface of the spray flange and the upper surface of the narrow portion of the casing may be widened or narrowed.

It is accordingly an object of my present invention to give a perfect spraying action, with free and proper adjustment according to the different pressure of various motive powers of fire-fighting pumps, and pumps used in other various purposes.

The drawing is a vertical view of the variable spray nozzle of this invention, with its right-hand half cut vertically through and a portion of its upper end cut away.

This invention relates to an improvement of a variable spray nozzle with the following mechanism. The casing 2 is connected to the end of pipe 1. The spray jet 3 is provided at the upper end of the said casing 2. The base of the narrow portion 4 of the said casing 2 is equipped with the divided water supplying holes 5, 5 geared with the male screw 6 at the lower outside of the said casing 2. Thus the branch stream straight shooting casing 7 is made to move back and forth by gyration. The inside of the upper end of the said branch stream straight shooting casing 7 and the outside surface of the narrow portion 4 of casing 2 are made to form the straight shooting jet 8. The spray cover 9 is screwed with the female screw 4' which is provided on the inside of the narrow portion 4 of the casing 2. The water supplying holes 10, 10 are provided at the middle side of the spray cover 9. The guide flange 11 is fitted at the upper end of the spray cover 9. The shallow groove 11' is provided at the top of the guide flange 11. By fitting the

2

end of driver in this shallow groove 11' and turning it, the space between the lower surface of the guide flange 11 and the upper surface of the narrow portion 4 of the casing 2 may be widened or narrowed.

Because of the above described mechanism of this variable spray nozzle, the water under pressure coming from the pipe 1 is divided by the divided holes 5, 5 provided at the base of the narrow portion 4 of the casing 2, passes through the inside of the branch stream straight shooting casing 7, and is jetted straight through the straight shooting jet 8. At the same time, the main stream jetted from the spray jet 3 through the water supplying holes 10, 10 of the spray cover 9 screwed at the inside surface of the narrow portion 4 of the casing 2 collides with the aforesaid straight shooting branch stream, producing sprinkled spray. The angle of sprinkling can be gradually narrowed by turning branch stream straight shooting casing 7 against the casing 2 and advancing it, and the space of the spray jet 3 can be widened or narrowed by turning the spray cover 9, thereby adjusting the amount of water and force of the main stream jetted from the spray jet 3 through the water supplying holes 10, 10 of the spray cover 9, and consequently making as effective and strong as possible the colliding and sprinkling action of the main stream against the straight shooting branch stream. Thus the variable spray nozzle of this invention can give a perfect spraying action, with free and proper adjustment according to the different pressures of various motive powers of fire-fighting pumps, and pumps used in farms and orchards for fire-fighting or spraying insecticides and fertilizer, and other pumps. This is indeed a very useful invention.

I claim as my invention:

40 1. A variable spray nozzle comprising a main cylindrical casing, an outer casing longitudinally movably mounted on said casing, said main casing and said outer casing being spaced apart in proximity to the discharge end of said nozzle 45 with portions thereof extending parallel to the axis of said main casing forming a straight water jet channel, water supply openings from said main casing opening into said channels, a spray guide cover for the outlet end of said main casing longitudinally movably mounted in the open discharge end of said main casing having a flange extending axially of said main casing, a spray guide flange on said spray cover adapted for coaction with the end of said main casing, spray water supply openings in the said flange of said

spray cover for radially directing water flow therefrom, said spray cover and said outer casing upon longitudinal movement thereof controlling the velocity and direction of flow of water streams emitted through the two sets of said openings and from said spray nozzle.

2. A variable spray nozzle comprising a main casing, screw threads on said main casing, an outer casing rotatably mounted on said main casing and operatively engaging said screw threads for longitudinal movement, said outer casing having an open discharge end, a first set of main water supply holes in said main casing, said main casing having a narrow upper portion, said main casing and said outer casing being spaced apart due to said narrow portion in proximity to said supply holes and forming a main water discharge channel communicating with said supply holes, said narrow portion being internally threaded, a spray cover for the outlet end of said main casing screwed into said narrow portion and

being longitudinally movable with respect thereto, a second set of spray water supply holes in the side of said spray cover for radial discharge of water therefrom, a guide flange on said spray cover of larger diameter than the end of said narrow portion, said flange coacting with the upper end of said narrow portion to control direction and velocity of flow from said spray holes from said nozzle.
